(57) **CLAIM**

The ornamental design for a solar cell, as shown and described.

DESCRIPTION

FIG. 1 is a front, left, top perspective view of a solar cell in accordance with our new design;

FIG. 2 is a front elevation view thereof;

FIG. 3 is a rear elevation view thereof;

FIG. 4 is a top view thereof;

FIG. 5 is a bottom view thereof;

FIG. 6 is a right side elevation view thereof;

FIG. 7 is a left side elevation view thereof;

FIG. 8 is a back, right, top perspective view thereof;

FIG. 9 is an enlarged detailed view of a portion of the solar cell of FIG. 1;

FIG. 10 is an enlarged detailed view of a portion of the solar cell of FIG. 4;

FIG. 11 is an enlarged detailed view of a portion of the solar cell of FIG. 5;

FIG. 12 is an enlarged detailed view of a portion of the solar cell of FIG. 6;

FIG. 13 is an enlarged detailed view of a portion of the solar cell of FIG. 8; and,

FIG. 14 is an enlarged detailed view of a portion of the solar cell of FIG. 8.

The broken lines shown in the figures depict portions of the solar cell that form no part of the claimed design.

1 Claim, 10 Drawing Sheets
